UNITED STATES PATENT OFFICE.

JOHN NATHAN, OF LOS ANGELES, CALIFORNIA.

THERMOSTATIC REGULATOR.

1,224,313.

Specification of Letters Patent.

Patented May 1, 1917.

Application filed February 8, 1915. Serial No. 6,924.

To all whom it may concern:

Be it known that I, JOHN NATHAN, a subject of Great Britain, residing at Los Angeles, in the county of Los Angeles and 5 State of California, have invented a certain new and useful Improvement in Thermostatic Regulators, of which the following is a specification.

My invention relates to a closed or open 10 circuit thermostat and has for its object to provide a device in which the circuit is broken and closed, respectively, by the expansion and contraction of a fluid, and in which the fluid is heated by a resistance 15 means in the circuit, whether in series or multiple therewith.

These and other objects are accomplished by the structure hereinafter specifically described in the accompanying drawing and 20 more particularly pointed out in the claims.

In the drawings

Figure 1 is a view illustrating my invention as applied.

Fig. 2 is an enlarged sectional elevation. 25 Fig. 3 is a section on line 3-3 of Fig. 2.

Fig. 4 is a sectional elevation of a slightly modified form.

Fig. 5 is a sectional elevation illustrating the application of my invention to boilers, 30 and Fig. 6 is a sectional elevation showing the employing of my invention in connection with unit heating systems.

Referring in detail to the drawing, in which like reference numerals denote like 35 parts, A designates a body, preferably of cylindrical form, and composed preferably of two parts, 1 and 2, the part 1 forming a chamber or container for a suitable fluid held therein by and acting upon a yielding 40 means, as a diaphragm 3, as in Fig. 2, which diaphragm, together with a heat insulating disk 4, is held between the abutting flanges 5 and 6 respectively, of the parts 1 and 2.

The liquid in the chamber or container 45 is heated by a resistance coil 7, having one of its terminals secured to a binding post 8, and its other end connected to a contact 9, on which is pivotally mounted a switch blade 10, adapted to engage a contact 11, to which 50 is attached a wire 12, as in Fig. 1, for completing the circuit. Said yielding diaphragm 3, is provided centrally thereof with a stem 13, having it free and connected to said blade 10 by a pin 14, operating in an 55 elongated slot 15. Surrounding said stem 13 is a coiled expansion spring 16, bearing at one end against said diaphragm and at

the other against the wall 17 of said part 2, and serving to return said diaphragm to normal position upon contraction of the 60 liquid and to bring the switch blade 10 in engagement with the contact 11. When the liquid, which is preferably of an easily volatilizable character, is heated to a sufficient degree, the ensuing expansion forces out the 65 diaphragm and the stem against the tension of the spring 13, and operates the blade 10, which, disengaging from the contact 11, breaks the circuit. On contraction of the 70 fluid, the diaphragm resumes its normal position under the tension of the spring, as explained.

Heretofore I have referred to a cylinder having a yielding means or diaphragm, as shown in Figs. 1 and 2 and 3. This yielding means may, however comprise a piston 75 18, slideable within the part 1, which occupies a position reverse to that of the part 1 in Fig. 2, for the purpose of preventing leakage of the fluid.

In Fig. 5 I have shown a method of applying my invention to a boiler. The part 2 of the cylinder may have a threaded flange 19, for engagement with one end of a boiler 20. Onto this part 2 is attached in any 85 manner the part 1, containing the liquid, which acts upon the diaphragm 3, by expansion produced by heating the liquid through the medium of a heating coil 7, which is preferably inclosed in a mica cov- 90 ering 21, through which the heat may pass to heat the water in the boiler, without coming in direct contact with the coil. One terminal of the coil is attached to the contact 9, on which is pivotally mounted the switch 95 blade 10, arranged for contact with a contact 11, to which the other terminal of the coil is secured. The blade is operated through the medium of the stem 13, connected with the blade, and with the dia- 100 phragm, in the manner described in connec- 105 tion with Fig. 2. The return of the dia- phragm 3 to normal position is effected by the coiled spring 16.

In Fig. 6 I have shown a method of using 110 the device in connection with unit heating plants, whereby, when a certain degree of heat is reached in a room, the steam or hot water, as the case may be, is automatically shut off from the particular unit furnish- ing the heat.

To the blade 10 is pivotally attached one end of an arm 22, the other end being attached to a lever 23, fulcrumed at 24. To

the end of the lever 23 is connected a lever 25, which operates a valve 26 in a pipe line 27, to control the flow of steam or water to a radiator 28. One of the terminals of 5 the heating coil 7, is connected to the binding post 8, which also serves to bind a wire 29, connected to a switch 30, and the other terminal is connected to the contact 11, on the part 2 of the cylinder. Attached to 10 the contact 9 is a wire 31, leading to the mercury or other fluid in a thermometer 32. In line with and leading from the graduations on said thermometer 32, is a plurality of wires 33, connected with fixed 15 contact plates 34 on a suitable base or support 35, of insulating material. Said base is provided with a slot 36, in which is a contact member 37, having an indicating hand 38, arranged to slide, such contact member 37 having attached thereto one end 20 of a wire 39, the other end being connected to said switch 30.

When a certain temperature is desired in a room, the indicating hand 38, is moved 25 to the corresponding graduation on the thermometer 32, such movement bringing the contact member 37 in contact with one of the plates 34. When the mercury or other fluid in the thermometer 32 reaches 30 the graduation at which the hand 38 is set, the circuit will be closed, and the coil 7 heated. The consequent expansion of the fluid in the part 1 of the cylinder, causes, in the manner heretofore described, the 35 blade 10, to disengage from the contact 11, and thus break the circuit. In this manner an even temperature may always be maintained.

In Fig. 2 I have illustrated a method of 40 regulating the tension of the coil spring 16, for the purpose of increasing or decreasing the sensitiveness of the yielding member 3 to the action of the expansive fluid, and thus regulating the heat according to 45 need.

To this end, the plate 17 is provided with an externally threaded tubular extension 40, through which the stem 18 passes, and on which is a nut 41, against which one 50 end of the spring 16 bears. By manipulation of said nut the tension of said spring is regulated.

What is claimed is:

1. A device for regulating the heat produced by an electric current, comprising a two part cylinder, a heat insulating material interposed between the conducting surfaces of said parts, a diaphragm between 55 said parts, a liquid in one part of said cylinder acting upon one face of said diaphragm, spaced contacts secured to said cylinder, a switch blade coöperating therewith, a stem connecting said diaphragm to

said blade, a coil spring encircling said stem to return said diaphragm to normal 65 position, and means included in the circuit for heating said liquid.

2. Means for regulating the heat produced by an electric current consisting of a chamber containing a liquid, a coil in 70 the heat producing circuit for heating the liquid, a circuit control, means acted on by the liquid to maintain a steady temperature of the liquid and the heat produced by the current, and means to regulate the temperature at which the liquid is to be maintained to thereby control the heat produced 75 by the current.

3. A device for regulating the heat produced by an electric current consisting of 80 a chamber for a liquid, a yielding means on said chamber, a heating coil in the circuit to heat the liquid in the chamber, contacts on said chamber, a circuit control co-operating therewith, means actuatable by said 85 yielding means under the movement of the liquid automatically to operate said circuit control and thereby regulate the heat of the liquid and the heat produced by the electric current, and means to regulate the 90 resistance of said yielding means to the movement of the liquid.

4. A device for regulating the heat produced by an electric current, comprising a receptacle for an expansible fluid, a means 95 arranged to yield under the expansion and contraction of the liquid in said chamber, a resistance coil in the circuit to heat the liquid in said chamber, a circuit controlling means operable by the movement of said yielding means to maintain a definite temperature of the liquid and heat produced by the electric current, and adjustable means 100 to predetermine the heat.

5. A device for regulating the heat produced by an electric current, comprising a chamber for an expansible liquid, a resistance coil in the circuit to heat the liquid in said chamber, a circuit control, a means on said chamber acted on by the expansion 105 of the liquid to operate said circuit control and break the circuit and to make the circuit when the liquid contracts thereby to govern the heat produced by the electric current, and means manually operable to 110 regulate the resistance of the means on said chamber to the expansive force of the liquid to control the temperature of the heat produced by the electric current.

In testimony whereof I affix my signature 120 in the presence of two witnesses.

JOHN NATHAN.
